[57] **ABSTRACT**

A process for joining the sleeve lining in sack coats and similar garments to the shoulder pads in the arm socket by means of a backstitch-blindstitch operation. The blindstitches are arranged so as to extend only partially through the shoulder pads so as to avoid stiffening the shoulder pads. The blindstitch operation is done on a backstitch-blindstitch type sewing machine. Prior to placing the lining and shoulder pads on the machine, the pertinent sleeve and coat structure is pulled through an opening in the sleeve lining. The invention also contemplates the construction of the sleeve lining, armhole part and shoulder pads with the blindstitches extending only partially through the shoulder pads.

**PROCESS FOR JOINING THE SLEEVE LINING IN
SACK COATS AND LIKE GARMENTS TO THE
SHOULDER PADS IN THE ARM SOCKET AND
CONSTRUCTION FORMED THEREBY**

**BACKGROUND AND SUMMARY OF THE
INVENTION**

The previous methods for joining the sleeve lining with the shoulder pads in the armhole consisted in connecting the sleeve lining on the overturned sack coat with the shoulder pads either by hand or by means of a normal quilted seam.

The procedure of accomplishing this operation manually is disadvantageous in that it is very time-consuming, and in that the hand-made seam is not very durable. The process of joining the sleeve lining with the shoulder pads in the arm socket by means of an ordinary quilted seam is disadvantageous, because, during the sewing step, the straight needle of the backstitch sewing machine penetrates the sleeve lining as well as the shoulder pads, so that the shoulder pads become too firm and too rigid. That is, the shoulder pads lose their desirable softness and elasticity due to the stitches extended therethrough by the straight needles.

It is contemplated by the present invention to replace the aforementioned processes by a novel, more advantageous procedure.

The solution contemplated by this invention is characterized in that the sleeve lining is joined with the shoulder pads in the arm socket by means of the double-thread seam of a backstitch-blindstitch sewing machine which comprises a lower feeder and an adjustable upper feeder, whereby a penetration of the stitch through the shoulder pads is avoided and an incorporation of the lining by means of the upper feeder is made possible.

The present invention contemplates the provision of a process of placing the shoulder pads and sleeve lining adjacent one another on a backstitch-blindstitch type sewing machine and sewing the pads and sleeve lining together with the machine in such a manner that the sewing stitches connecting the pads and sleeve lining extend only partially through the shoulder pads.

The present invention also contemplates the provision of a construction for sack coats and the like including an armhole part, shoulder pad attached to said armhole part and a sleeve lining attached to said armhole part by way of blindstitches extending through said sleeve lining and armhole part but only partially through said shoulder pads.

These provisions and other objects, features and advantages of the present invention will become more apparent from the following detailed description thereof, when taken in conjunction with the accompanying drawings.

BRIEF DESCRIPTION OF THE DRAWINGS

FIG. 1 illustrates a sack coat sleeve and armhole construction according to the previous manual procedure;

FIG. 2 illustrates an armhole construction wherein the sleeve lining is joined to the shoulder pads by an ordinary quilted, or backstitch seam;

FIG. 3 illustrates an armhole construction wherein the sleeve lining is joined to the shoulder pads in accordance with the novel process of the present invention by the seam of a backstitch-blindstitch sewing machine; and

FIG. 4 illustrates the sewing of the sleeve lining in the armhole construction of FIG. 3 on the sewing machine.

In FIG. 1, 1 denotes the fabric of a reversed sack coat, 2 denotes the sack coat lining, and 3 is the sleeve lining. This sleeve lining 3 is shown as cut open at point 3a for illustrating the two-piece shoulder pad 4 and 4a. Hand-basted seam 5 joins the sack coat lining 2 with the shoulder pads 4, 4a. Seam 6 joins the linings 2 and 3.

10 In FIG. 2, the fabric of the sack coat is again denoted by 1, 2 again denotes the sack coat lining, and 3 the sleeve lining, while 3a is again a small, turned-over portion of the sleeve lining 3 under which a portion 2a of the sack coat lining 2 is visible. The sack coat lining 2 and/or 2a is again joined with the shoulder pads 4, 4a by means of a basted seam 5. Numeral 7 in FIG. 2 designates an ordinary quilted seam, during the sewing of which the long, straight, and vertically disposed needle of an ordinary backstitch sewing machine penetrates 15 through the sack coat lining 2 (and/or 2a) and also additionally completely through the shoulder pads 4 and 4a, and sews these parts together. As mentioned in the introduction, this arrangement attaches the shoulder pads too rigidly with consequent disadvantages. In FIG. 2, 8 denotes the cylindrical lower arm of a backstitch sewing machine employed in this embodiment.

20 FIG. 3 shows an armhole construction in accordance with the novel process of the present invention. The backstitch-blindstitch seam 9 is extended by a blindstitch into the outer padding part 4 of the shoulder pad 4, 4a in as shallow a manner as possible by means of an ordinary circularly curved needle. The thread of seam 9 extends through the sack coat lining 2 and the sleeve lining 3 and into the outer padding 4 of the shoulder pads. Blindstitch seam 9 comprises two threads disposed side-by-side on the sleeve lining 3.

25 The shoulder pads 4 and 4a have been connected to one another to form a coherent element in all three processes by basting seams prior to introduction into the arm socket. Preferably the blindstitch only extends into outer part 4. However, depending on the dimensions of parts 4 and 4a, the stitch could possibly extend into part 4a, particularly if part 4 were very thin. Also, a one-piece pad could be used.

30 In FIG. 4, 8 denotes the cylindrical lower arm and 10 the head of the backstitch-blindstitch machine particularly suitable for purposes of the present invention. The machine under protection as German Utility Model Pat. No. 1,953,464 of the firm J. Strobel & Soehne could be used with the present invention.

35 The disclosure of said Utility Model is incorporated by reference herein to the extent necessary for understanding the disclosure of the present invention.

40 In the machine illustrated, 11 denotes the cloth clamping plate pressing the layers of fabric 1, 2, 3, 4, and 4a against the so-called needle plate or stitchplate 12. The needle plate 12 has a wide slot 13 through which the layers of fabric are forced, by a conventionally perpendicularly or vertically reciprocating presser element (not shown in the drawings), precisely to such an extent that the curved needle (likewise not shown), which swings to-and-fro on a needle lever 14, penetrates just barely in a blind manner, i.e., without a penetrating stitch, into the shoulder pad part 4.

45 In accordance with the novel process of this invention according to FIGS. 3 and 4, it is additionally noted that the arm socket with the shoulder pads and the por-

tions of the lining must be pulled through the open elbow seam or inner seam of the sleeve lining before being introduced into the machines. Each sleeve lining consists of two parts, a front part and a rear part. Both parts are closed by a quilted or backstitched seam on the left-hand and right-hand sides (and/or on the inside and on the outside as seen from the sack coat viewpoint). For this reason, prior to pulling the arm socket through the sleeve lining, the inner quilted seam (inner seam of the sleeve lining) must remain open along a sufficient length for this pulling operation.

After the sleeve lining 3 has been sewed on in the aforementioned machines, the open section of the inner seam of the sleeve lining 3 is again closed by means of a quilted seam.

It is additionally of great importance for the process of this invention that the backstitch-blindstitch sewing machine utilized in this connection possesses, in addition to the normal lower feeder, an upper feeder or feeder dog which is adjustable during the sewing operation. This adjustability of the feeders with respect to one another enables the sewing machine operator to incorporate the width of the lining into the arm socket in an accurate manner and to a required extent. The blindstitch seam employed in the novel process of the present invention exhibits advantageous effects in many respects. This seam is more elastic than a normal quilted seam. Also, since the two sewing threads are disposed on the sleeve lining, increased protection is attained against premature abrasion of the seam produced by constant chafing during the wearing of the garment and, in the final analysis, against detaching of the sleeve lining.

While I have shown and described one embodiment in accordance with the present invention, it is to be understood that the same is not limited thereto but is susceptible of numerous changes and modifications as known to a person skilled in the art, and I therefore do not wish to be limited to the details shown and described herein but intend to cover all such changes and modifications as are within the scope of those skilled in the art when given the disclosure herein.

I claim:

1. A process for joining, in the area of an armhole part of a sack coat or like garment, a sleeve lining to shoulder pad means provided in said armhole part, said process comprising:

placing the shoulder pad means and sleeve lining adjacent one another on a backstitch-blindstitch type sewing machine, and

sewing the shoulder pad means and sleeve lining to one another with said sewing machine in such a manner that sewing stitches connecting the shoulder pad means and sleeve lining extend only partially through said shoulder pad means.

2. A process according to claim 1, wherein said sewing machine has a first and second feed means and a circular stitching needle, and wherein said step of placing includes positioning the sleeve lining and shoulder pad means between said first and second feed means in such a manner that said circular stitching needle first engages said sleeve lining during the sewing step.

3. A process according to claim 2, wherein said first feed means is a lower feeder and said second feed means is an adjustable upper feeder, said sleeve lining being positioned closer to said upper feeder than are said shoulder pad means.

4. A process according to claim 2, wherein the armhole part is provided with a coat lining, and wherein said process comprises the further step of positioning said coat lining on said sewing machine so as to be stitched together with said shoulder pad means and sleeve lining during the sewing step.

5. A process according to claim 2, further comprising the step of reversing the normal in-use position of said coat structure by pulling the armhole part along with the shoulder pad means and sleeve lining through an open inner seam of the sleeve lining prior to the step of placing.

10 6. A process according to claim 4, further comprising the step of reversing the normal in-use position of said coat structure by pulling the armhole part along with the shoulder pad means and sleeve lining through an open inner seam of the sleeve lining prior to the step of placing.

15 7. A process according to claim 4, further comprising the step of closing up said open inner seam of the sleeve lining after the step of sewing the shoulder pad means to said sleeve lining.

20 8. A process according to claim 4, further comprising the step of attaching said shoulder pad means to said coat lining of the armhole part prior to the step of placing.

25 9. A process according to claim 2, wherein said shoulder pad means is formed in two parts which are attached to one another prior to the step of placing.

10 10. A process according to claim 8, further comprising the step of closing up said open inner seam of the sleeve lining after the step of sewing the shoulder pad means to said sleeve lining.

30 11. A process according to claim 6, wherein said coat lining, sleeve lining and shoulder pad means are positioned such that said circular needle first engages said sleeve lining, then said coat lining, and then said shoulder pad means.

35 12. A process according to claim 11, further comprising the step of pulling the armhole part along with the shoulder pad means and sleeve lining back through said open inner seam so that the coat structure is in the normal position for use.

40 13. A process according to claim 12, further comprising the step of closing up said open inner seam of the sleeve lining after the step of sewing the shoulder pad means to said sleeve lining.

45 14. A construction for sack coats and the like comprising: an armhole part, shoulder pad means attached to said armhole part, and a sleeve lining attached to said armhole part by way of blind stitches extending completely through said sleeve lining and armhole part and only partially through said shoulder pad means.

50 15. A construction according to claim 14, further comprising an inside lining on said armhole part also attached by said blind stitches extending therethrough.

16. A process according to claim 4, wherein said first feed means is a lower feeder and said second feed means is an adjustable upper feeder, said sleeve lining being positioned closer to said upper feeder than are said shoulder pad means.

55 17. A process according to claim 6, wherein said first feed means is a lower feeder and said second feed means is an adjustable upper feeder, said sleeve lining being positioned closer to said upper feeder than are said shoulder pad means.

60 18. A process according to claim 11, wherein said first feed means is a lower feeder and said second feed means is an adjustable upper feeder, said sleeve lining being positioned closer to said upper feeder than are said shoulder pad means.
